UNITED STATES PATENT OFFICE.

SPENCER G. NEAL, OF LOS ANGELES, CALIFORNIA, ASSIGNOR TO CALIFORNIA VALVE
AND AIR BRAKE COMPANY, OF LOS ANGELES, CALIFORNIA, A CORPORATION OF
CALIFORNIA.

AUXILIARY-PRESSURE-CONTROL VALVE.

1,089,575.

Specification of Letters Patent.

Patented Mar. 10, 1914.

Application filed July 29, 1913. Serial No. 781,833.

To all whom it may concern:

Be it known that I, SPENCER G. NEAL, a citizen of the United States, residing in the city of Los Angeles, State of California, 5 have invented a new and useful Auxiliary-Pressure-Control Valve, (Case A,) of which the following is a specification.

In the operation of railway braking systems now in general use, no provision is 10 made to safeguard against over-charging the auxiliary reservoirs after there has been a service application of the brakes. That is to say, although the auxiliary reservoir pressure is not apt to be over-charged in the 15 original charging of the train pipe and the auxiliary reservoirs, nevertheless, after there has been an application of the brakes and it is desired to again charge the train pipe through the engineer's brake valve, 20 this second or subsequent charging of the train pipe not infrequently results in over-charging the same, thereby increasing the pressure in the train pipe until it exceeds the pressure for which the feed valve is set, 25 the feed valve being set to maintain in the train pipe the required pressure for full release of the brakes. The result of this excessive pressure in the train pipe will be a tendency to raise the auxiliary reservoir 30 pressure to an equality with this excessive train pipe pressure, which tendency will result in charging the auxiliary reservoir above the pressure for which said feed valve is set. Therefore, when the engineer's brake 35 valve is later placed in running position, thus cutting off free communication between the train pipe and the main reservoir and allowing the feed valve to control the train pipe pressure, the train pipe pressure will 40 be reduced from this excessive pressure to the pressure for which the feed valve is set, which will bring the train pipe pressure below that in the auxiliary reservoir, thus causing undesired service application of the 45 brakes.

In a braking system provided with this pressure control valve it is possible to over-charge the train pipe five pounds or other predetermined amount, without over-charging 50 the auxiliary reservoir.

It is to be understood that this newly invented pressure control valve is to be assembled in combination with a triple valve

constructed according to the principle of the triple valve described and claimed in my 55 Patent No. 1,078,303, dated Nov. 11, 1913. In order to adapt the triple valve of said pending patent to coöperate with the pressure control valve hereinafter described, it is not necessary to modify the construction 60 of said triple valve but only to dispense with the charging valve of the same as will hereinafter more fully appear.

Referring in detail to the accompanying drawings which illustrate the invention, Fig. 1 is a vertical mid-section of this pressure control valve. Fig. 2 is a section similar to Fig. 1, but the movable parts are shown in a different operative position. Fig. 3 is a diagram of braking elements of a car 70 provided with the invention. Fig. 4 is a view reproducing with slight change the fifth view of my above mentioned patent.

Referring in detail to the drawings, in the diagram shown in Fig. 3, 5 is the brake cylinder, 6 the auxiliary reservoir, 7 the triple valve and 8 the control valve proper. Said control valve 8 is connected by means of a pipe 9 with the auxiliary reservoir 6. A pipe 11 connects control valve 8 to the train 80 pipe 12. The triple valve 7 is provided with a branch pipe 14 leading to the train pipe 12.

Referring now to the construction of the control valve proper, the casing thereof comprises a lower cap 15, an upper cap 16 and a 85 spacing ring 17. Said caps and spacing ring have interposed between the same diaphragms 18 and 19 these parts all being clamped together by the cap screws or bolts 21. Within the casing and between the dia- 90 phragms 18 and 19 is a spacer 22 having an upwardly extending head or stem 23, playing within a tubular extension 24 projecting upwardly from the upper cap 16. Said extension 24 has a stop screw 25 through the 95 top thereof and lock nut 26 to hold said stop screw in the adjusted position. The inner end of said screw 25 limits the upper movement of head 23. The diaphragm spacing device 22 is also provided with a 100 downwardly extending valve stem 27 terminating at its lower end in valve 28, which engages the valve seat 29. Through said valve 28 and stem 27, and the body of the spacer 22 extends a passage 31, said passage 105 leading up into the top extension 23, there

100
105

being radial ports 32 which lead out from the passage 31, to the auxiliary reservoir chamber 33 located above the upper diaphragm 18. In the illustrated embodiment of the invention, the lower diaphragm 19 is of less working area than the upper diaphragm 18, these two diaphragms being so proportioned to each other that when the pressure in the upper chamber 33 has reached a point within five pounds of that in the lower chamber 34, valve 28 will be seated. The valve stem 27 is guided by an upwardly extending boss 35, there being a small valve chamber 36 around said valve 28. Ports 37 lead from said chamber 36 to the train pipe chamber 34. Beneath valve 28 an auxiliary reservoir passage 41 leads out through the pipe 9. A train pipe passage 42 and pipe 11 lead to the train pipe 12. Vents 45 lead to the outer atmosphere from annular atmospheric chamber 46, located between the inner diaphragm supports 47 and 48. Further detailed explanation of the general construction of the diaphragm device will not be necessary because said device is constructed along the lines set forth in Patent No. 1,062,300 issued to G. C. Pierce May 20th, 1913. The working area of the lower diaphragm 19 is less than the working area of the upper diaphragm 18 by reason of the lower diaphragm recess 49 being of less diameter than the upper diaphragm recess 51; and also by reason of the fact that the annular ledge 52 contracts the lower portion of the spacing ring 17.

Referring in detail to Fig. 4, this view is a reproduction of the charging valve shown in Fig. 5 of my Patent No. 1,078,303, dated November 11, 1913, except that nut 55 secured to the top of valve stem 56 is screwed down so as to prevent charging valve 57 from leaving its seat, thereby rendering said charging valve inoperative. The charging function, as before stated is performed by charging valve 28 of the present invention.

Operation: In the operation of charging the auxiliary reservoir, train pipe pressure will enter the pressure control valve 8, (see Fig. 3) through the branch pipe 11 passing into the chamber 34, and will raise the pressure against the lower side of the lower diaphragm 19 to raise said diaphragm and unseat valve 28, thereby permitting air to pass through ports 37, and valve chamber 36 down through passage 41 and pipe 9 to the auxiliary reservoir 6. As the pressure in the auxiliary reservoir increases, the same will be registered in auxiliary reservoir chamber 33 owing to said chamber 33 being in communication with passage 41 at all times through passage 31 and ports 32. This flow of air will continue until the pressure in the auxiliary reservoir chamber 33 above diaphragm 18 reaches to within five pounds of the pressure beneath the lower diaphragm.

19, at which time, owing to the lesser working area of the lower diaphragm 19, the diaphragm device will descend closing the valve 28 and cutting off further entrance of air to the auxiliary reservoir.

I claim:

1. The combination with the train pipe, auxiliary reservoir and triple valve, of a pressure control device comprising a casing, two diaphragms dividing said casing into three chambers, the chamber between said diaphragms being in free communication with the outer atmosphere; one of said outer chambers being an auxiliary reservoir chamber, and the other of said outer chambers being a train pipe chamber; the diaphragm next to the auxiliary reservoir chamber having a greater working area than the other diaphragm, a spacing device rigidly uniting said diaphragms, a passage leading from the auxiliary reservoir chamber through said spacing device, and an extension forming a valve through which said passage opens out, said valve controlling communication between the train pipe and the auxiliary reservoir, and said passage through said valve at all times affording communication between the auxiliary reservoir and said auxiliary reservoir chamber.

2. The combination with the train pipe auxiliary reservoir and triple valve, of a pressure control device comprising a casing, two diaphragms within said casing dividing the same into three compartments, one of the outer chambers being in communication with the auxiliary reservoir and the other outer chamber being in communication with the train pipe, the diaphragm next the auxiliary reservoir chamber being of greater working area than the diaphragm next the train pipe chamber, and means operated by said diaphragm device to control communication between the train pipe and the auxiliary reservoir.

3. In combination, a train pipe, an auxiliary reservoir, a triple valve, a movable abutment comprising two elements of different areas, a casing divided by said abutment into two chambers exteriorly thereto, a valve consisting of a tube having an open end within its seating surface, said valve being operatively connected with said abutment and controlling communication between the train pipe and the auxiliary reservoir, the movements of said abutment being controlled by train pressure opposed by auxiliary reservoir pressure, the tubular portion of said valve communicating with the auxiliary reservoir chamber.

4. In combination, a train pipe, an auxiliary reservoir, a triple valve, a casing, an abutment within said casing comprising two elements of different areas, said abutment dividing said casing into an auxiliary reservoir chamber and a train pipe chamber ex-

terior thereto, and means controlled by the movements of said elements to maintain in said auxiliary chamber a pressure less than the pressure in said train pipe chamber.

5 In testimony whereof I have hereunto signed my name in the presence of two subscribing witnesses at Los Angeles, in the

county of Los Angeles and State of California, this 24th day of July 1913.

SPENCER G. NEAL.
